DESIGN FOR A DIM-OUT SHIELD FOR AUTOMOBILE HEADLIGHTS

Nathan Cooper, New Haven, Conn.

Application June 3, 1942, Serial No. 107,084

Term of patent 3½ years

To all whom it may concern:

Be it known that I, Nathan Cooper, a citizen of the United States, residing at New Haven, in the county of New Haven and State of Connecticut, have invented a new, original, and ornamental Design for Dim-Out Shield for Automobile Headlights, of which the following is a specification, reference being had to the accompanying drawing, forming part thereof.

Figure 1 is a view in front elevation of a dim-

out shield for automobile headlights, showing my new design.

Figure 2 is a view in side elevation thereof.

Figure 3 is a vertical section taken on the line 3—3 of Figure 1.

I claim:

The ornamental design for a dim-out shield for automobile headlights, as shown.

NATHAN COOPER.
